US00D991271S

(12) **United States Design Patent** (10) Patent No.: **US D991,271 S**
McNeil et al. (45) Date of Patent: ** Jul. 4, 2023

- (54) **DISPLAY SCREEN WITH AN ANIMATED GRAPHICAL USER INTERFACE**
- (71) Applicant: **Dapper Labs Inc.**, Vancouver (CA)
- (72) Inventors: **Courtney McNeil**, Vancouver (CA); **Donald Dundas McErory Flavelle**, Abbotsford (CA); **Denise Cascelli Schwenck Bismarque**, Vancouver (CA); **Catherine Marzi Tedman**, Vancouver (CA)
- (73) Assignee: **Dapper Labs, Inc.**, Vancouver (CA)
- (**) Term: **15 Years**
- (21) Appl. No.: **29/781,845**
- (22) Filed: **Apr. 30, 2021**
- (51) LOC (14) Cl. **14-04**
- (52) U.S. Cl. **USPC D14/485**
